[57] CLAIM

The ornamental design for a sterilization case, as shown and described.

DESCRIPTION

FIG. 1 is a top, front, and left side perspective view of a sterilization case, showing my new design;

FIG. 2 is a front elevational view thereof;

FIG. 3 is a right side elevational view, the left side being

a mirror image thereof;

FIG. 4 is a top plan view thereof;

FIG. 5 is a rear elevational view thereof;

FIG. 6 is a bottom plan view thereof; and

FIG. 7 is a perspective view in the open position.

*FIG. 2**FIG. 3**FIG. 4*FIG. 5

FIG. 6

FIG. 7
